UNITED STATES PATENT OFFICE.

SAMUEL L. MOTT, OF NEWARK, NEW JERSEY, ASSIGNOR OF TWO-THIRDS
TO CHARLES B. CAMPBELL AND CHARLES G. CAMPBELL, BOTH OF
SAME PLACE.

RUNNING-BOARD FOR FREIGHT-CARS.

SPECIFICATION forming part of Letters Patent No. 427,598, dated May 13, 1890.

Application filed April 7, 1890. Serial No. 346,874. (No model.)

To all whom it may concern:

Be it known that I, SAMUEL L. MOTT, a citizen of the United States, residing at Newark, in the county of Essex and State of New Jersey, 5 have invented certain new and useful Improvements in Running-Boards for Freight-Cars; and I do hereby declare the following to be a full, clear, and exact description of the invention, such as will enable others skilled in the 10 art to which it appertains to make and use the same, reference being had to the accompanying drawings, and to letters of reference marked thereon, which form a part of this specification.

15 The present invention relates to a combined safety and running board for freight-cars, and has for its object to provide the terminating ends of the running-boards on such cars with pivoted or hinged boards or bridges, 20 which are so constructed as to extend from one car to another when coupled, and thereby form a continuous running-board from end to end of train.

25 A further object of the invention is to construct such connecting-bridges in sections which are adapted to be folded one upon the other, whereby the bridge can be brought from its hanging position and connected with the next car after the cars have been coupled.

30 Furthermore, the invention consists in providing the running-board of a car near its ends with a means for holding or locking the bridge or connecting-board of the rear or last car in a vertical position, which acts as a safety-board and prevents the train-men from accidentally stepping off a car on a dark night.

35 In the accompanying sheet of drawings, in which similar reference-letters are used to indicate corresponding parts, Figure 1 represents a train of cars in side elevation provided with my improved running-boards. Fig. 2 is a plan view of the same. Fig. 3 shows the ends of two adjoining cars, illustrating the positions of the different parts of 40 the jointed connecting-board while being raised from its vertical or hanging position onto the next car; and Fig. 4 represents a running-board provided with a means for holding or locking the connecting-board in a 45 vertical position.

In the accompanying drawings, A represents the running-board on the top of a freight-car, which has secured thereto to its extremities by means of hinges *b* or in any other like manner the connecting boards or bridges 55 *a*. As will be clearly seen from Figs. 2 and 3, said bridges *a* are constructed to be folded in the middle, and are made of two pieces *a'* and *a''*, which are jointed or pivotally secured together by means of hinges *b'*. These boards 60 or bridges *a*, when not in use, may be allowed to hang down the side of the cars, as is clearly illustrated in Fig. 1, or the same can be thrown back upon its hinges *b*, so that it will lie on the running-board A, as shown to the right of 65 Fig. 2. When in this position, the board *a* can simply be thrown over onto the next car when they have been coupled; but when hanging in a vertical position between two coupled cars the bridges as heretofore made 70 could not be raised so as to communicate with the next car. As clearly shown in Fig. 3, this difficulty has been overcome by constructing the board of two pieces and connecting them by means of the hinges *b'*, whereby the bridge 75 can readily be raised and the part *a''* thrown on the next car, as will be evident from said figure. The hinges *b'* are of such a construction that when the board *a* connects two cars they will tend to hold the parts *a'* and *a''* in 80 a straight line and stiffen the same, so that a train-hand can safely walk over the bridge. The end of the parts *a''* of the bridge may be chamfered, as at *a''*, to cause the same to slide freely upon the running-board of the 85 next car, which is of great advantage, especially when two cars of different heights are coupled together, as shown at the left of Fig. 1. In Fig. 4 is illustrated one means for holding or locking the connecting-bridge in 90 position at a right angle to the running-board. By this means the board at the end of the last car of a train can be held in this position, and thereby acts as a guard and prevents the train-hand from accidentally jumping off the 95 car.

The construction shown in Fig. 4 consists of attaching to one or both sides of the running-board on a car a rod *c*, secured by means of a staple or pin *c'*, provided with a hook *c''*, 100

which engages with an eye or staple a^4 on the side of the connecting-board when the latter is raised in a vertical position.

Having thus described my invention, what I claim is—

1. A freight-car provided on either or both ends with a bridge or platform consisting of two hinged portions adapted to be folded one upon the other, one of which is hinged to the 10 extremity of the running-board on one car, while the other portion is caused to rest upon the top of the next car, upon which it may freely slide, said bridge being adapted by means of the hinged portions to be raised 15 from its hanging position between two cars when coupled, as and for the purposes set forth.
2. The combination, with two coupled freight-cars, of a connecting board or bridge consisting of portions a' and a^2 , secured by 20 means of hinges b' , one of said portions, as a' , being attached by means of hinges b to one car, whereby said board may be raised from its hanging position between said cars and thrown over onto the next car without 25 uncoupling said cars, as and for the purposes set forth.
3. In combination with the roof of a car,

the running-board provided with connecting boards or bridges made up of sections adapted to be folded one upon the other, for the purposes set forth. 30

4. In combination with the roof of a car, the running-board provided with connecting boards or bridges made up of sections adapted to be folded one upon the other, and one of 35 said sections being chamfered at its free end, which, when the cars are coupled, rests upon the top of the running-board of the next car and slides thereon, as and for the purposes set forth. 40

5. A freight-car provided on either or both ends of the running-board with a hinged or pivoted connecting board or bridge and means for holding or locking said board in a vertical position, as and for the purposes set forth. 45

In testimony that I claim the invention as set forth above I have hereunto set my hand this 4th day of April, 1890.

SAMUEL L. MOTT.
